UNITED STATES PATENT OFFICE.

HOWARD EARL HOOVER, OF CHICAGO, ILLINOIS, ASSIGNOR, BY MESNE ASSIGNMENTS,
TO THE HOOVER COMPANY, OF NORTH CANTON, OHIO, A CORPORATION OF OHIO.

SUCTION-CLEANER HANDLE.

Application filed February 14, 1919. Serial No. 276,911.

To all whom it may concern:

Be it known that I, HOWARD EARL HOOVER, a citizen of the United States, residing at Chicago, in the county of Cook and State 5 of Illinois, have invented a certain new and useful Improvement in Suction-Cleaner Handles, of which the following is a specification.

My invention relates to handles for vacuum cleaners and has for its object to provide means whereby the handle and bail may be secured together in such manner as to easily permit take-up as the handle shrinks and to properly align the handle 15 when it is brought into position. The means by which I accomplish this result are illustrated in the accompanying drawings wherein,

Figure 1 is a bottom view of a handle and 20 bail;

Figure 2 is a side elevation thereof;

Figure 3 is a detailed longitudinal section along the line 3—3 of Figure 1;

Figure 4 is a detail of a modified device 25 for connecting the handle to the bail, and

Figure 5 is a still further modification.

Like parts are indicated by the same letter in all the figures.

A is the bail adapted to be secured at the 30 pivotal points B B to the vacuum cleaner.

C is a socket, secured to, or integral with the bail. This socket is tapered as indicated and is preferably formed with a central annular off-set D. This leaves it with 35 two interior ring-like surfaces E and F

which make contact with the tapered end G of the handle H. J is a longitudinal slot in the socket and K K are conductor holding attachments on the side of the handle. L is a bolt having a head M let in a recess N in the side of the tapered end of the handle. The bolt passes through a hole in the tapered end of the handle and in through the slot J and is screw-threaded 40 at O to receive the thumb nut P. The washer R is interposed between the thumb nut and the side of the socket and it overlies the slot. In the first modification the socket C is provided with an opening C¹

50 in its end and through this opening projects the wood screw S screw-threaded at T to receive the thumb nut U. V is a washer between the end of the socket and the lock washer Z¹. W is a pin secured to the handle and adapted to enter the longitudinal

slot J in the socket. In the second modification the parts are the same as illustrated in Figure 4 except that Y is a screw which enters the side of the socket and projects into the slot Z in the end of the taper of 60 the handle.

It will, of course, be understood that I do not wish to be limited to the size, proportion and arrangements of these several parts because other wide variations can be 65 made without departing from the spirit of my invention and my drawings are to be taken as in a sense diagrammatic although they are for the particular form of device here shown in effect working drawings. 70

The use and operation of my invention are as follows:—

With vacuum cleaners such as those for which this handle is intended, the handle is not uncommonly made of wood but 75 whether made of wood or not, it is liable to shrinkage or such variation as to make it loose in the socket. Occasionally the handle may be removed and then when it is reinserted, particularly by an unskillful operator, it is not infrequently difficult to bring 80 it to the proper alignment so that the cord or cable attachments will be in the desired position with reference to the bail and the suction cleaner. The user or careless operator will endeavor in various ways to force the handle into position in the socket or will endeavor to force it rotatably into position so as to bring the parts into proper 85 alignment. 90

This will tend to strip the threads. The object is to avoid having either a loose handle or an imperfectly aligned handle.

With my invention the difficulties and dangers incident to such conditions are entirely obviated. The handle is in each case permanently and constantly in proper alignment and it has no occasion to rotate and is not adapted to be rotated. The pin or bolt as the case may be which passes through or 100 into the slot being rigidly secured to handle or bail prevents rotational movement of the handle on the bail but permits longitudinal movement.

The desired or necessary longitudinal movement for the insertion of the handle or for the take-up in the event of the parts having shrunk or changed their relative sizes is easily accomplished with the device of 105 Figures 1 and 2 by loosening the thumb 110

nut and forcing the handle longitudinally into the tapered socket. When it has reached its proper position the thumb nut is operated so as to grip the side of the socket between the washer or thumb nut and the handle. Thus the parts are securely locked in position and the more so because any tendency of the handle to move outwardly is resisted not only by the normal friction of the parts but by the fact that the side of the socket is inclined to the line of movement of the handle. In the case of the device illustrated in Figures 4 and 5 the handle is in like manner forced in any desired way into the socket and of course it may be drawn into the socket at least in part by operating the thumb nut but in any event when in its extreme position it is secured by turning the thumb nut.

These devices are commonly made of aluminum and metal somewhat difficult to machine but the handle at least at the mouth of the socket should be in secure contact therewith to avoid rocking or movement of the handle in the socket of the bail. I reduce the difficulty of machining and insure a good contact by hollowing out or forming an annular recess on the inside of

the socket leaving a smooth finished outer band or ring about the handle at the mouth of the socket. This results in the handle being securely held within the socket and reduces to a minimum the tendency of the handle to work in the socket in any manner and thus reduces to a minimum the strain on the securing parts and their tendency to get out of operative condition.

I claim:

A handle comprising a part adapted to be secured and provided with a tubular socket, a handle shaft having an end adapted to be received in the socket, a pin attached to the handle shaft and projecting through a longitudinal slot in the socket and a thumb nut on the outside of the pin overlying the slot whereby rotational movement of the handle in the socket is prevented and longitudinal movement may be permitted or prevented at the will of the user.

In testimony whereof, I affix my signature in the presence of two witnesses this 10th day of February, 1919.

HOWARD EARL HOOVER.
